TREATMENT OF HYDROCARBON OILS

Luis de Florez, Pomfret, Conn., assignor to The Texas Company, New York, N. Y., a corporation of Delaware

Application April 27, 1933, Serial No. 668,180

6 Claims. (Cl. 196—94)

This invention relates to the treatment of hydrocarbon oils, such as those derived from petroleum, and more particularly to the fractionation of mixed hydrocarbon vapors such as those produced when hydrocarbon oils are subjected to cracking to promote the formation of lower-boiling oils such as gasoline, naphtha, gas oil or the like.

An object of my invention is to provide a method of fractionating mixed hydrocarbon vapors containing constituents of different boiling points for the recovery of a number of constituents therefrom, whereby light constituents, such for example, as gasoline, may be separated from heavier constituents as well as lower-boiling constituents or gases and recovered in a suitable and desirable form.

My invention has for further objects such additional improvements in operative advantages and results as may hereinafter be found to obtain.

My invention contemplates delivering mixed hydrocarbon vapors, such, for example, as a mixture of normally gaseous constituents, gasoline constituents, gas-oil constituents, and intermediate constituents having boiling points lying between the boiling points of said gasoline and gas-oil constituents, to a fractionating zone wherein they are progressively cooled to effect a condensation of relatively high-boiling constituents, such, for example, as gas-oil constituents, and preferably also a fraction comprising somewhat lower-boiling or intermediate constituents.

My invention further contemplates the removal of uncondensed vapors and gases from the fractionating zone, cooling the same to effect a condensation of low boiling constituents such as gasoline, and separating the condensate thereby obtaining from the remaining gases. The separated condensate is then flashed to a lower pressure to remove gases contained therein and the gases withdrawn from the separating zone and also the gases withdrawn from the flashing or weathering zone are treated with absorbent oil to remove normally liquid constituents which may be present therein in vapor form.

Preferably the treatment of the gases removed from the separating and flashing or weathering zones is carried out by means of condensate or condensates separated from the vapors in the fractionating zone, and the enriched condensate or condensates after treatment of the gases is or are returned to the fractionating zone as reflux. In the preferred form of my invention, the gases removed from the separating zone are treated substantially without reduction of pressure with

relatively heavy condensate such, for example, as gas oil, while the gases liberated in the flashing or weathering zone are treated with relatively light condensate, such for example, as a heavy naphtha fraction withdrawn as a side stream 5 from the fractionating zone.

In other embodiments of my invention, however, the gases withdrawn from the separating and flashing zones may be combined for treatment with a single absorbent oil or may be treated in separate stages with a single absorbent oil, which may be either a relatively heavy condensate such as gas oil or an intermediate condensate such as a heavy naphtha fraction.

Where an intermediate fraction is employed for 15 the purpose of treating gases withdrawn from the separating zone or the flashing zone or both, it is preferably first stripped, as for example, by treating it with steam in suitable apparatus, before being contacted with the gases treated, for the 20 purpose of removing low-boiling constituents which would interfere with or reduce the efficiency of the subsequent treatment of the gases.

My invention further contemplates the provision of a combined cracking and fractionating 25 system wherein a petroleum oil such, for example, as a reduced crude or a gas oil may be cracked to effect a conversion of the oil to lower boiling constituents such as gasoline and the like, the vapors being fractionated in the manner recited hereinabove.

In order that my invention may be clearly set forth and understood, I now describe, with reference to the drawing accompanying and forming part of this specification, various preferred forms and manners in which my invention 35 may be practiced and embodied. In this drawing,

The single figure is a more or less diagrammatic elevational view of apparatus for effecting 40 the cracking of a hydrocarbon oil and the fractionation of the resultant vapors in accordance with my present invention.

Referring now to the drawing, mixed hydrocarbon vapors under a superatmospheric pressure of for example from 50 to 200 pounds per square inch, are supplied from a source thereof, such, for example, as a primary fractionating tower or still 1, by means of a vapor-transfer line 2 having a valve 3 to a fractionating tower 4, the interior of which is provided with plates or trays 5 of suitable design. The plates or trays 5 may comprise the conventional bells and trays commonly employed in fractionating vapor mixtures or any other gas-and-liquid-contact ap- 55

paratus suitable for the fractionation of such mixtures.

By means of cool reflux oil introduced to the fractionating tower 4 through conduits 6, 7, 7' or any of these, or by means of cooling effected in any other manner, the vapors passing through the fractionating tower 4 are subjected to progressive cooling and condensation while being maintained meanwhile under a suitable superatmospheric pressure of, for example from 50 to 200 pounds per square inch, to such extent as to remove higher boiling constituents, such as gas oil, and where desired, a fraction comprising intermediate constituents such as naphtha, leaving uncondensed the vapors or relatively low boiling constituents such as light naphtha or gasoline. The latter, together with fixed gases and vapors of constituents lighter than are desired to be included in the finished gasoline, escape from the top of the fractionating tower 4 through a vapor line 8 having a valve 9 and leading to a condenser 10.

The relatively high-boiling constituents removed from the vapors entering the tower 4 collect in the bottom of the latter, from which they may be withdrawn through a conduit 12 having a valve 13 or a conduit 14 having a valve 15, while intermediate or heavy naphtha constituents may be withdrawn as a side stream 30 from a trap-out tray 16 located at a suitable point in the tower 4 through the conduit 17 having a valve 18. The intermediate fraction thus withdrawn from the trap-out tray 16 may be passed through the conduit 19 having a valve 20 to a stripper 22 which is provided with a steam inlet 23 as well as plates or trays 24. By contact with the steam within the stripper 22, such low-boiling constituents as may be present in the intermediate fraction withdrawn from the trap-out tray 16 are volatilized and may be returned through a vapor line 25 to the fractionating tower 4 while the stripped intermediate condensate passes from the bottom of the stripper 22 through a line 26 leading to a cooler 27. Where the intermediate condensate withdrawn from the trap-out tray 16 does not require stripping, as for example, when it is withdrawn merely for the purpose of providing a reflux cooling effect in the fractionating tower 4, the side stream withdrawn from the trap-out tray 16 may be by-passed around the stripper 22 through a by-pass line 28 having a valve 29 and communicating with the conduits 17 and 26.

In the condenser 10 the vapors and gases leaving the top of the fractionating tower 4 are cooled by indirect contact with water, preferably to a substantially atmospheric temperature, thereby effecting the condensation of low-boiling constituents such as gasoline, and the mixture of condensed and uncondensed hydrocarbons passes through a conduit 31 to a separator 32, the upper portion of which may be provided with a plurality of separating baffles 33 for the purpose of assisting in the separation of the gases and the gasoline distillate. The separated gases pass from the separator 32 through a gas line 34 having a valve 35 to a scrubber or absorber 36, the interior of which is provided with plates or trays 37 or other suitable gas-and-liquid-contact means.

The gases thus entering in the scrubber 36, which normally contain some gasoline vapors, are treated for the removal of the latter by means of absorbent oil introduced to the upper portion of the scrubber 36 through a conduit 38.

In the preferred instance, gas oil removed from the bottom of the fractionating tower 4 through the conduit 14 is delivered through the conduit 38 to the scrubber 36, after first passing through a cooler 39 wherein it is cooled to substantially atmospheric temperature by indirect contact with water or otherwise.

The gases entering the base of the absorber 36 and passing upwardly therethrough under a pressure upward of 30 pounds per square inch, are scrubbed in countercurrent fashion by means of the absorbent oil entering the upper portion of the absorber 36 through the conduit 38 and are thereby stripped of their content of vapors of gasoline or other normally liquid constituents and leave the upper portion of the absorber 36 in substantially dry condition through a conduit 41 having a valve 42 and communicating with a gas main 43. The enriched absorbent oil reaching the bottom of the absorber 36 is withdrawn through a conduit 44 having a valve 45 and a pump 46. By means of the pump 46 the enriched condensate is returned either to the top of the distillation vessel 1, through a branch conduit 47 having a valve 48 and communicating with the top of the vessel 1, or through a conduit 50 having a valve 51 and branch conduits 52 or 53 to either or both of the inlets 7 and 7', respectively, in the fractionating tower 4. In the preferred instance, the enriched gas oil from the bottom of the fractionating tower 36 is returned in part to the top of the primary fractionating tower 1 and in part through the conduits 44, 50, 53, and 7' to an intermediate level in the fractionating tower 4, a valve 54 in the conduit 52 being closed for the purpose of preventing flow of this oil into the top of the fractionating tower 4.

The condensate collected in the bottom of the separator 32 under a pressure only a little below that obtaining in the upper portion of the tower 4, and consisting of raw gasoline containing undesirable light or gaseous constituents dissolved therein, is wholly or in part withdrawn from the separator 32 through a pipe 60 having a pressure-reducing valve 61 and flashed into the interior of a weathering drum 62 maintained at a pressure substantially below that obtaining in the separator 32, for example, a pressure of from 1 to 15 pounds per square inch. The drum 62 may be provided with a coil 63 for steam or other heating fluid for the purpose of assisting in the removal of the gases or other undesirable light constituents from the gasoline, and also with baffles 64 for the purpose of assisting in the separation of gases and gasoline.

By means of the pressure reduction incident to the flashing of the gasoline from the separator 32, which may be assisted as aforesaid by heat supplied from the coil 63, raw gasoline entering the weathering drum 62 is freed from gases dissolved therein and the resultant weathered gasoline is withdrawn from the bottom of the weathering drum 62 through a conduit 65 having a valve 66, while the liberated low-pressure gases which, although small in amount inevitably contain a considerable proportion of vapors and low-boiling normally liquid constituents pass from the top of the weathering drum 62 through a conduit 67. By means of a branch conduit 68 having a valve 69 and a compressor 70, these gases and vapors may be delivered to the scrubber 36 for treatment together with the gases and vapors leaving the separator 32, but in the preferred instance they are caused to pass through a conduit 75.

72 having a valve 73 to a low-pressure scrubber 74 having interiorly-disposed plates or baffles 75 and supplied with absorbent oil through a conduit 76 having a valve 77. In the preferred instance this absorbent oil comprises cooled intermediate oil which, after having been withdrawn from the trap-out tray 16 in the fractionating tower 4, has been stripped in the stripper 22 and cooled in the cooler 27 and is thus in condition for effecting the removal from the gases entering the scrubber 74 of low-boiling normally liquid constituents such as light gasoline ends.

The scrubbed gases leave the scrubber 74 in a substantially dry condition through a conduit 78 having a valve 79 and communicating with a gas main 81, while the enriched absorbent oil reaching the bottom of the scrubber 74 is withdrawn therefrom through a conduit 82 having valves 83 and 84 and a pump 85, by means of which the enriched absorbent oil is returned to the fractionating tower 4. In reintroducing this oil into the fractionating tower 4, the valves 54 and 51 as well as valves 86 and 87 and the inlets 1 and 1', respectively may be manipulated so as to cause all of this oil to pass into the upper portion of the fractionating tower 4 through the inlet 1 or so as to divide the flow of absorbent oil between the inlets 1 and 1'.

By means of a branch 90 having a valve 91 and communicating with the conduits 82 and 41 a portion of the enriched condensate oil from the scrubber 74 may also be returned to the top of the primary fractionating tower 1 to serve as reflux therein, this procedure being especially desirable where the treatment of the gases in the scrubbers 36 and 74 is carried out entirely by means of intermediate condensate withdrawn from the trap-out tray 16 in the fractionating tower 4.

As has been indicated hereinabove, the preferred procedure is to pass the relatively high-pressure gases from the separator 32 to the scrubber 36 and the relatively low-pressure gases from the weathering drum 62 to the scrubber 74, the scrubbing medium in the scrubber 36 comprising cooled gas oil withdrawn from the bottom of the fractionating tower 4 and the scrubbing medium in the absorber 74 comprising cooled and stripped intermediate oil withdrawn from the trap-out tray 16. In this instance, the enriched gas oil from the bottom of the absorber 74 is preferably returned in part to the primary fractionating tower 1 and in part through inlet 1' into the fractionating tower 4 while the enriched intermediate oil from the bottom of the absorber 74 is returned from the inlet 1 to the top of the fractionating tower 4.

I may, however, accomplish the treatment of the relatively high-pressure gases in the absorber 36 and the relatively low-pressure gases in the absorber 74 by means of separate portions of the intermediate oil withdrawn from the trap-out tray 16. In this instance, the valve 15 is closed and a portion of the oil leaving the cooler 27 is withdrawn through a branch conduit 94 having a valve 95 and communicating with the conduit 38 through which this portion of the intermediate oil passes to the absorber 36.

It may be noted at this point that there is ordinarily a sufficient pressure differential between the fractionating tower 4 and the scrubber 36 to permit oil withdrawn from the former to flow to the latter without the use of pumps, but pumps may be provided wherever the pressure in the scrubber 36 is too close to that in the fractionating tower 4 to dispense with their use.

I may also, where desired, accomplish the treatment of the gases liberated from the separator 32 and the weathering drum 62 entirely by means of gas oil withdrawn from the bottom of the fractionating tower 4. I provide a conduit 96 having a valve 97 and communicating between the conduits 16 and 38 for the purpose of delivering a portion of the gas oil from the cooler 39 to the absorber 74 in addition to that portion which is normally delivered through the conduit 38 to the scrubber 10 36. In this instance, the valves 77 and 95 are closed and if a side stream is withdrawn from the trap-out tray 16, it is ordinarily returned from the cooler 27 to the fractionating tower 4 through a conduit 101 having a valve 102 and a pump 103 15 and communicating with the conduit 6. Alternatively, however, the valve 18 may be closed and the reflux oil supplied through the conduit 6 to the fractionating tower 4 may comprise condensate removed from the separator 32 through 20 a conduit 104 having a valve 105 and a pump 106 and also communicating with the reflux conduit 6.

Where the gases withdrawn from the weathering drum 62 are passed by means of the compressor 10 and the conduit 68 into the absorber 36, the absorbent oil employed in the absorber 36 may comprise intermediate oil from the trap-out tray 16 or gas oil from the bottom of the fractionating tower 4 as desired. In this as in other instances the enriched absorbent oil is returned 30 to the fractionating tower 4, as well as to the tower 1 wherein a preliminary fractionation takes place as will be shown hereinbelow, in such amounts and proportions as to effect the desired fractional condensation of the vapors. 35

Where the absorbers 36 and 74 are both employed, however, the relatively high-pressure gases from the former pass into the main 43 while the relatively low-pressure gases from the latter pass into the main 81. The main 43, which may 40 be at a pressure of 30 pounds or more, is usually in communication with the principal plant gas main, whereas the main 81 may lead to nearby burners employed for heating associated cracking or distilling apparatus. In the instance shown, I 45 have provided communication between the high-pressure main 43 and the low-pressure main 81 through a valve 110, which is preferably automatically operated to supply high-pressure gas from the main 43 to the main 81 in sufficient 50 quantity to augment the volume of the low-pressure gases to such extent as may be desired for any purpose.

While my invention may be utilized for the fractionation of mixed hydrocarbon vapors of 55 various kinds and from various sources, it is especially useful for the fractionation of vapors produced in the cracking of hydrocarbon oils and may advantageously be combined with the cracking of hydrocarbon oils. In the instance illustrated 60 in the accompanying drawing, I have illustrated apparatus for carrying out a preferred cracking process which may be advantageously combined with the fractionating methods set forth hereinabove. 65

According to this method of operation, an oil to be cracked and thereby reduced to lower-boiling oils and residue is introduced into the still 1 from a source (not shown) through the conduit 111 wherein is located a pump 112 and which 70 terminates in two branches 113 and 114 having valves 115 and 116 respectively, leading to different points in the tower 1. The interior of the tower 1 may be provided with baffles 117 and a tray or plate 118 for the purpose of promoting 75

contact between the charging oil thus introduced and vapors introduced into the tower 1 through a vapor line 120 leading from the reaction vessel or coking drum 121. The latter is preferably supplied with cracked hydrocarbon vapors through a transfer line 122 from a heating coil 123 which in the preferred instance illustrated receives gas oil withdrawn from the fractionating tower 4 through the conduit 12. A pump 124 is located 10 in the conduit 12 for the purpose of delivering this gas oil under a proper pressure to the coil 123.

In the preferred instance, the recycled gas oil withdrawn from the fractionating tower 4 is 15 passed by means of the pump 124 through the heating coil 123, wherein it is raised to a relatively high cracking temperature of, for example, from 850° to 1050° F. under a pressure of from 200 to 750 pounds per square inch, and the resultant cracked products are discharged through the transfer line 122 into the coke drum or reaction vessel 121 where a separation of liquid and vapors occurs as well as a continuation of the cracking inaugurated in the heating coil 123. 20 The hot cracked vapors then pass through the vapor line 120 into the tower 1 where they are brought into contact with fresh charging oil introduced by means of the pump 112 and a combined dephlegmating and vaporizing action takes 25 place. Residual portions of the charging oil together with heavy condensate removed from the cracked vapors are withdrawn from the bottom of the still 1 through a conduit 130 having a valve 131 and a pump 132 and communicating with the transfer line 122, preferably through an injector 133. In this manner, combined residue and condensate from the bottom of the tower 1 may be brought to a cracking or coking temperature in the vessel 121 without the necessity of passing it 30 through a pipe coil, and the pipe coil 123 is provided with clean stock, i. e., gas oil withdrawn from the bottom of the fractionating tower 4, which may be carried to a very high cracking temperature without excessive deposition of carbon 35 therein.

While the cracking system set forth hereinabove represents a type of process with which the fractionating methods of my present invention may advantageously be combined, it will be obvious to those skilled in the art that my fractionating system may be applied to and used in conjunction with other types of cracking systems.

Furthermore, while I have illustrated and described my invention with respect to various illustrative examples and instances, it will be understood that my invention is not limited to the details of such exemplifications, but is broadly 60 to be construed in accordance with the scope of the claims hereinafter made.

I claim:

1. The method of fractionally condensing mixed hydrocarbon vapors containing normally 65 gaseous constituents, gasoline constituents, gas-oil constituents and intermediate constituents having boiling points lying between the boiling points of said gasoline and gas oil constituents, which comprises delivering said vapors to a fractionating zone maintained under superatmospheric pressure wherein said vapors are progressively cooled, separately removing a gas-oil fraction and an intermediate fraction at separate points in said fractionating zone, stripping said 70 intermediate fraction of gasoline constituents

present therein, removing uncondensed vapors and gases from said fractionating zone, cooling them to condense gasoline constituents, separating the condensed gasoline from the remaining vapors and gases, scrubbing said vapors and gases with a cooled portion of said gas-oil fraction to remove gasoline constituents therefrom and returning the thereby enriched gas oil to said fractionating zone, flashing the condensed gasoline to a lower pressure to remove gases and undesirable 10 low-boiling constituents therefrom, scrubbing the thereby liberated gases and vapors with said stripped intermediate fraction to remove gasoline constituents therefrom and returning the thereby enriched intermediate fraction to said 15 fractionating zone.

2. The method of fractionally condensing mixed hydrocarbon vapors containing normally gaseous constituents, gasoline constituents, and higher boiling constituents, which comprises delivering 20 said vapors to a fractionating zone maintained under superatmospheric pressure wherein said vapors are progressively cooled, removing condensate comprising higher-boiling constituents from said fractionating zone, cooling said condensate, removing uncondensed vapors and gases from said fractionating zone, cooling them to condense gasoline constituents, separating the condensed gasoline from the remaining vapors and gases, scrubbing said vapors and gases with 30 condensate from said fractionating zone to remove gasoline constituents therefrom and returning the thereby enriched condensate to said fractionating zone, flashing the condensed gasoline to a lower pressure to remove gases and undesirable 35 low-boiling constituents therefrom, removing condensate from said fractionating zone and stripping lighter constituents therefrom, scrubbing the gases and vapors liberated from the condensed and flashed gasoline to remove gasoline 40 constituents therefrom, with cooled stripped condensate from said fractionating zone and returning the thereby enriched condensate to said fractionating zone.

3. The method of fractionally condensing mixed 45 hydrocarbon vapors which comprises delivering said vapors to a fractionating zone maintained under superatmospheric pressure wherein said vapors are cooled to effect a condensation of relatively high boiling constituents, removing un- 50 condensed vapors from said high-pressure fractionating zone, cooling them to condense relatively high boiling constituents thereof, separating the condensate from the uncondensed gases and vapors, flashing the condensate to a lower pressure to liberate gases and vapors of lower boiling constituents thereof, scrubbing said uncondensed gases and vapors first mentioned in a first scrubbing zone with a relatively high boiling condensate absorbent oil removed from said fractionating 60 zone, scrubbing the gases and vapors liberated from said flashing stage in a second scrubbing zone, separate from said first scrubbing zone, with a lower boiling condensate absorber oil removed from said fractionating zone, and distilling resultant enriched absorber oil to separate desired 65 lighter fractions therefrom.

4. A method in accordance with claim 3 wherein in said resultant enriched absorber oil is distilled by being introduced into said high pressure fractionating zone.

5. A method in accordance with claim 3 where- 70 in the enriched absorber oil is removed from said first scrubbing zone and is introduced into an intermediate point in said high pressure fraction- 75

ating zone and enriched absorber oil is removed from said second scrubbing zone and is returned to an intermediate point in said high pressure fractionating zone higher than the point to which 5 the absorber oil from said first scrubbing zone is returned.

6. The method of fractionally condensing mixed hydrocarbon vapors which comprises delivering said vapors to a fractionating zone maintained under superatmospheric pressure wherein 10 said vapors are cooled to effect a condensation of relatively high-boiling constituents, removing from said fractionating zone at least a portion of the condensate thereby obtained, stripping condensate so removed of relatively low-boiling constituents and cooling the stripped condensate, removing uncondensed vapors from said fractionating zone and cooling them to effect condensation 15 of relatively low-boiling constituents, flashing

said low-boiling constituents to a lower pressure in a weathering zone to liberate gases contained therein, scrubbing said liberated gases at said lower pressure, to remove vapors therefrom, with a portion of said stripped and cooled relatively 5 high-boiling condensate from said fractionating zone, returning the thereby enriched condensate to said fractionating zone, passing light gases and vapors remaining uncondensed after the cooling of the uncondensed vapors removed from said 10 fractionating zone, to an absorbing zone of higher pressure than said weathering zone and therein scrubbing said light gases and vapors with another portion of the said stripped and cooled relatively 15 high-boiling condensate from said fractionating zone to remove desired constituents therefrom, and returning the thereby enriched condensate to said fractionating zone.

LUIS DE FLOREZ.
